UNITED STATES PATENT OFFICE.

ARTHUR H. SCOTT, OF PHILADELPHIA, PENNSYLVANIA.

SUPPORTING DEVICE FOR PACKAGES.

1,106,003.

Specification of Letters Patent.

Patented Aug. 4, 1914.

Application filed January 24, 1907. Serial No. 353,850.

To all whom it may concern:

Be it known that I, ARTHUR H. SCOTT, of the city and county of Philadelphia, State of Pennsylvania, have invented an Improvement in Supporting Devices for Packages, of which the following is a specification.

My invention has reference to supporting devices for packages of toilet paper and consists of certain improvements which are 10 fully set forth in the following specification and shown in the accompanying drawings which form a part thereof.

In Letters Patent No. 765,599, granted to me on July 19th, 1904, I have shown a device for supporting packets of toilet paper in a case, consisting of a backing provided at its top with an open inverted triangular pocket adapted to receive a supporting tongue or hook of the case.

20 My present invention relates to a device of this character and more particularly consists of improvements in the pocket structure, whereby greater strength and efficiency are obtained. My improvements also include means for attaching the pocket to the 25 paper package.

More specifically, my invention consists in forming the pocket and retaining or securing means of an integral piece of sheet 30 metal, the pocket being formed of sheet metal having its edges bent over upon the body of the sheet, and the attaching means consisting of a tongue bent at right angles to the plane of the pocket.

35 My invention also comprehends details of construction which, together with the features above specified, will be better understood by reference to the drawings, in which:

40 Figure 1 is a perspective view of a paper packet embodying my invention; Fig. 2 is a vertical section of the upper part of the same; and Fig. 3, is a perspective view of a modified form of the sheet metal pocket 45 and securing means.

A is the package of toilet paper, B is the metallic pocket at the back of the package of paper, and C is the securing tongue which extends through the paper package and has 50 its free end bent over as at D on the opposite

side of the said package. The tongue C and the pocket B are preferably made of one integral piece of sheet metal. The construction of the pocket may be made in various ways, all of which comprehend the essential 55 characteristics of a pocket open from below, adapted to the back of the package of paper and connected to said package of paper by the securing tongue or its equivalent.

Referring to the construction shown in 60 Figs. 1 and 2, the pocket is made triangular with the outer plate B continuous and with the upper edges thereof turned over to form flanges E E preferably meeting at the top and adapted to form grooves or recesses F 65 into which the support may enter when the package is placed in the case or cabinet as more particularly set out in my patent hereinbefore referred to. The tongue C is preferably formed integral with one of the 70 flanges E, but bent at right angles thereto so as also to be at right angles to the plate B and plane of the pocket as a whole. In this construction, the tongue C is at the upper part of the pocket. 75

Referring to Fig. 3, the plate forming the pocket has its side edges E' bent inward corresponding to what is shown in Fig. 1, and in this instance the tongue C is made integral with one of said side flanges. There 80 being no top flange in this form, the corners H H may be bent over so as to form oblique closures for a portion of the upper part to sustain the pocket and package upon the supporting arm of the cabinet. I have 85 shown the side flanges in this instance with their lower edges oblique, but this is not essential as these lower edges may be otherwise formed if so desired.

These various examples of my improved 90 supporting device will explain the general construction of my improvement, but it will be understood that the minor details may be varied in many ways without departing from the essential characteristics of the invention set out in the appended claim. 95

Having now described my invention, what I claim as new and desire to secure by Letters Patent, is:

A supporting device for a paper packet 100

which consists of an inverted socket formed of sheet metal having its edges bent over to form oblique grooves and having the metal of one of said edges extended at right angles to and wholly to one side of the plane of the socket to form a tongue for securing the paper packet to the socket.

In testimony of which invention, I have hereunto set my hand.

ARTHUR H. SCOTT.
